UNITED STATES PATENT OFFICE.

ALEXIS GODILLOT, OF NEW YORK, N. Y.

DESIGN FOR SARDINE-BOX.

Specification forming part of Design No. **7,942**, dated December 22, 1874; application filed October 24, 1874.
[Term of Patent 7 years.]

To all whom it may concern:

Be it known that I, ALEXIS GODILLOT, of the city, county, and State of New York, have invented a Design for a Sardine-Box, of which the following is a specification:

The object of my invention is to furnish for the trade a neater and more ornamental box for French sardines, the nature of which is fully represented in the accompanying perspective drawing, to which reference is made.

A represents a sardine-box, made of the usual material, but of oblong octagonal shape, the shorter straight sides B at the corners serving as the additional space for the display of the trade-mark, or other suitable distinctive ornamentation. Raised beads C run along the upper and lower edges of the sides of the

box, forming thereby a kind of border for the middle part, for the better display of the names and figures thereon, while giving at the same time the advantages of a better hold to the fingers in handling the boxes. The outer appearance of the box becomes more marked and ornamental, and therefore more attractive as an article of commerce.

I claim as my invention—

The design for a sardine-box of oblong octagonal shape, with raised border beads running along the sides, substantially in the manner as shown and described.

ALEXIS GODILLOT.
